UNITED STATES PATENT OFFICE.

LEON KNASTER, OF UNION CITY, NEW JERSEY.

SECRET CABINET.

Application filed April 28, 1923, Serial No. 635,370. Renewed May 20, 1926.

In my Letters Patent No. 994,009, issued May 30, 1911, I have described a novel type of secret cabinet useful in the home, in offices, and other places, for the purpose of secreting

5 papers or articles of a personal nature, or such as may be of a private kind appertaining to business or other organizations, papers or articles which it is desired to take especial care of.

10 My present invention involves improvements in cabinets such as presented in the above identified Letters Patent, the primary objects in view regarding the new construction now to be set forth including provisions

15 for a main secret compartment of greater dimensions, or content area, than in my previous construction; a main compartment which is protected more adequately against burglary and fire than that heretofore proposed;

20 the provision of an auxiliary secret compartment adjacent to the main secret compartment, adapted to receive and hold papers of less value and importance; the rendering of the secret compartments more difficult of ac-

25 cess than heretofore, when the same are closed, and using, constructing, and arranging the said compartments that their contents may be more readily accessible when the access as authorized incident to the opening of

30 the compartments by a person having knowledge thereof and equipped with the necessary means.

In the carrying out of my invention, my main secret compartment is so constructed by 35 the use of fireproof means and a strong enclosing chamber, that my complete cabinet, which is preferably in the form of a desk or secretary, would have to be demolished before the most inner secret compartment space

40 can be broken into.

Furthermore, in the carrying out of my invention, I have employed a special artistic design of desk or secretary that may, of course, be modified to embody different

45 adaptations, the primary intent being to produce a handsome piece of period furniture of which any owner may be proud, and which may not only be useful but ornamental in large and small homes, or other places where

50 a cabinet of the nature of the invention may be desired to be used.

A full understanding of the construction of my secret cabinet desk, or article of furniture, will be had on reference to the drawings annexed hereto, the figures of which may be

60 Figure 1 is a perspective view of a desk or secretary, the legs of which are broken away, the desk being open as when in use as an ordinary secretary.

65 Figure 2 is a vertical sectional view of the upper or cabinet portion of the desk as when out of use, the parts in closed positions, dotted lines illustrating the extent of normal movement of the drawer for permitting use 65 of the desk for ordinary writing purposes, or exposing the entire contents of the drawer itself.

70 Figure 3 is a view similar to Figure 2, excepting that the drawer is in open position and the dotted lines illustrate an additional or abnormal movement of the drawer, as well as the cover for the pigeon holes of the desk, which abnormal movement is permitted 75 by operation of special interlocking means, as a preliminary to obtaining access to the secret compartment.

75 Figure 4 is a sectional view taken about on the line 4-4 of Fig. 3, showing latch means for limiting withdrawal of the 80 drawer beyond its normal limits of movement.

80 Figure 5 is a sectional view, broken away, taken about on the line 5-5 of Fig. 3, looking upwards, and showing more fully the 85 main latch actuator for the drawer.

85 Figure 6 is a sectional view similar to Fig. 4, but showing the drawer in its extreme withdrawn position, as well as the cover for the pigeon holes, the top of the desk being 90 also moved forward so as to enable the large letter or file tray to be removed, and the back of the desk to be swung open as when it is desirable to have access to said tray, and to the lock boxes of my main secret 95 compartment.

95 Figure 7 is a perspective view of the lock box drawer which forms the secret compartment.

100 Figure 8 is a front elevation of the desk open.

105 Figure 9 is a rear elevation of the desk illustrating the parts practically as they are shown in Fig. 6, and certain parts being broken away to illustrate the secret chambers of the lock box drawer or secret compartment.

110 Passing now to a detailed description of my invention and referring to Fig. 1, my desk or cabinet comprises the body A, consisting of a base mounted upon legs B, which may be designed after the manner of any pe-

riod style furniture. The body of the desk comprises the cabinet section C which is designed artistically and is equipped with pigeon holes 1 of any suitable nature and arrangement desired. In front of the pigeon holes 1 is the table section 2, which forms a writing surface in conjunction with the folding leaf 3 which is preferably hinged at 4 at the front portion of the cabinet. A suitable drawer 5, such as very commonly provided for cabinets of this kind, is utilized and is mounted to slide in and out at the front portion of the cabinet section C, beneath the table section 2, as well as the pigeon holes 1. I preferably use any ordinary lock 6 and key 7 for preventing any unauthorized access to the drawer 5, and said drawer is fairly spacious to accommodate reception of papers or other articles of no great importance. The drawer 5 is susceptible of a normal opening movement limited by a secret catch 8, seen best in Fig. 4, as comprising a member pivoted at 9 and formed with a nose adapted to engage in front of the rear or inner wall 5^a of the drawer and thus prevent the drawer from being pulled outwards under normal conditions. The catch 8 is spring braced by means of the spring 10, see Fig. 4 also, and said catch is engaged at its lower portion by an actuator consisting of a manual lever 11, see Fig. 5, pivoted at 12, to the underside of a partition 13, that provides between the section 2 and the drawer a secret space in which my special main secret compartment is provided.

The lever 11 has a finger piece 11^a which is located near the front of the drawer opening, but substantially invisible because countersunk in the recess of the partition 13, and because carried by the underside of said partition. In front of the pigeon holes 1 is a curved cover 14, adapted to be moved slidably in suitable guides in the sides of the cabinet section C. This cover 14 is connected by metal straps 15, and curved links 16, with brackets 17 on the rear side of the wall 5^a on the drawer 5, the arrangement being such that as the drawer is pulled outwards the cover 14 is moved inwards toward the dotted line position of Fig. 2, or the full line position of Fig. 3.

The cover 14 has a normal opening movement corresponding with the normal opening movement of the drawer 5, enabling use of the desk for ordinary purposes, but when the drawer 5 is released from the catch 8 by operation of the manual lever 11, the availability of which is known only to the person authorized to have access to the secret compartment of the desk, the cover 14 may be given an abnormal movement by pulling the drawer 15 outwardly beyond the distance permitted when the catch 8 is operative to engage the wall 5^a of the drawer. The abnormal

movement which may be thus produced upon the cover 14 will carry it to a position substantially as shown in Fig. 6, or the dotted line position shown in Fig. 3, thereby rendering accessible the front end of a movable catch lever 17 which is countersunk in a recess in the top 18 of the cabinet section C. The catch lever 17 is pivoted at 19 to the top 18, and the latter is slidable forwardly and rearwardly upon the sides of the cabinet section C when the catch lever 17 has been disengaged by pivotal movement from a catch 20 at the top of the back 21 of the section C. There may be two of the catch levers 17, one at each side of the cabinet, or a single one may be employed as desired. The latter construction is used with a mounting of the lever 14 centrally of the top 18 and the catch 20 centrally of the back 21, best shown in Fig. 9, and Figs. 2, 3 and 6.

It will be apparent that when the cover 14 is in the position of Fig. 6, a person may readily apply his fingers to the outer end of the catch lever 17, and by shifting the same pivotally, disengage said lever from the catch 20. Thereupon the top 18 may be pulled outwards to the position of Fig. 6, and the back 21 may be opened. Said back 21 is pivoted at 22 to the rear portion of the cabinet section C, and its opening movement is limited by links 23. When the back is open it forms a little auxiliary table and the adjustment of the parts 18 and 21, as shown in Fig. 6, renders accessible the file or tray 24 disposed in the rear portion of the cabinet section C, and providing an auxiliary secret compartment especially adapted to hold files or large papers or documents of less importance than those contained in my innermost and main secret compartment, which is designated 25 in Fig. 6, and which is located primarily beneath the pigeon holes 1. Suitable guides 27 at the inner faces of the guide section C of the cabinet, guide the file holder or auxiliary secret compartment 24 as the latter is lifted upwards for removal or reinserted for replacement purposes relatively to the cabinet. My innermost and main secret compartment 25 comprises a chamber consisting preferably of inner and outer metallic walls 28 between which is provided an insulation 29 of asbestos or other fireproof substance. The chamber is adapted to receive a lock box drawer 30, the front wall of which consists of spaced metallic members 31, between which insulation 29 is also located. The body of the drawer 30 comprises a series of box like compartments closed at the top by lids 32 adapted to be locked individually by a suitable lock designated 33. On the front of the drawer 30 is provided a permutation lock 34, the combination of which will be known to the owner of the desk or those in his confidence who have authorized right to have

access to the secret compartments of the said desk.

Obviously, by reason of the construction of the compartment and the front wall of the compartment 25 and the front wall of the box 30, the chamber 25 is rendered fireproof, and it is moreover so strong and so well built into the cabinet section C of the secretary that it could not be entered by unauthorized persons without practically demolishing my whole cabinet. Additionally, of course, it is rendered fireproof which is very desirable, having in view the purposes of my cabinet.

15 A special advantage of my invention resides in the fact that while the secret compartments are very difficult of access to one unacquainted with the method of obtaining access thereto, nevertheless they can be almost instantly opened whenever it is desired to consult the contents either of the auxiliary compartment comprising the file holder 24, or the innermost secret chamber 30. The parts utilized to prevent unauthorized access to these compartments are very simply formed, being made primarily of metal stampings so far as the catches are concerned, and they are susceptible of easy manipulation. When the drawer 5 is pulled to its abnormal limit of withdrawal movement it co-operates with the member 11, to hold the catch inactive.

I preferably provide for the sliding movement of the top 18 by applying metal plates 35 to the upper edges of the sides of the cabinet section C, and securing slide plates 36 to the underside of the top 18, the latter being bent to overlap the plates 35 and afford a sort of metal rail interlock between said parts. Under these conditions, the sliding movement of the top 18 outwardly and inwardly is rendered very easy, and at the same time a very strong connection between the top and sides of the section C is afforded.

45 It will also be apparent that in the carrying out of my present invention, I have availed of a number of the novel features of construction of the cabinet of my previous Letters Patent, the same being embodied in a somewhat more substantial, artistic, and more practical and commercial construction, as previously set forth herein, as well as affording a much larger secret space area.

It will be evident that the pigeon holes 55 1 really form a public compartment for the desk or cabinet, that the cover 14 is a closing means for said public compartment, and that the drawer 5 constitutes an operating means for the member 14 to render it possible to obtain access to the compartments 30 and 24.

Having thus described my invention, what I claim as new and desire to secure by Letters Patent, is:

65 1. In a secret cabinet, the combination of a body having a secret compartment accessible from the rear thereof, a public compartment at the front of the body, means for closing said public compartment, an openable, movable back for affording access to said secret compartment, the body aforesaid including a top cooperating with said back, locking means for said movable back beneath the top and normally inaccessible incident to movement of the said closing means to merely expose the public compartment, said closing means being adapted for abnormal movement to render said locking means operable, said locking means remaining substantially concealed in the abnormal movement before mentioned.

2. In a secret cabinet, the combination of a body having a secret compartment, a public compartment at the front of the body, means for closing said public compartment, an openable, movable back for affording access to said secret compartment, locking means for said movable back normally inaccessible incident to movement of the said closing means to merely expose the public compartment, said closing means being adapted for abnormal movement to render said locking means operable, and means connected with the back to hold the same in a substantially horizontal position to act as a sort of table when it is opened for access to the secret compartment.

3. In a secret cabinet, the combination of a body including a top and having a secret compartment accessible from the rear thereof, a public compartment at the front of the body, means for closing said public compartment, an openable, movable back for affording access to said secret compartment and constituting the rear wall of the cabinet, locking means for said movable back mounted on the top above the closing means and normally inaccessible incident to movement of the said closing means to merely expose the public compartment, said closing means being adapted for abnormal movement to render said locking means operable, and means for controlling the normal and abnormal movement of said closing means of the public compartment.

4. In a secret cabinet, the combination of a body having a bodily movable secret compartment accessible from the rear thereof, a public compartment at the front of the body, means for closing said public compartment, an outwardly swinging cabinet wall for affording access to said secret compartment, locking means engageable with said movable wall normally inaccessible incident to movement of the said closing means to merely expose the public compartment, said closing means being adapted for abnormal movement to render said locking means operable, and a drawer at the front of the cabinet operatively connected with said

closing means of the public compartment to actuate the same.

5. In a secret cabinet, the combination of a body having a secret compartment accessible from the rear thereof, a back openable to enable access to said compartment, a top member, a drawer at the front of the cabinet, a locking means for said back concealed beneath the top and disposed to engage a co-10 operating means on the back, and means connected to the drawer for rendering said locking means accessible by movement of said drawer.

6. In a secret cabinet, the combination of a body having a main secret compartment, an auxiliary secret compartment comprising a bodily displaceable file holder normally preventing access to said main compartment, means preventing access to said auxiliary secret compartment, and parts operable to initially permit access to said file holder, and subsequent movement thereof to afford access to the main secret compartment.

7. In a secret cabinet, the combination of a body having a main secret compartment, an auxiliary secret compartment comprising a bodily removable file holder normally preventing access to said main compartment, means preventing access to said auxiliary secret compartment, and parts operable to initially permit access to said file holder, and subsequent movement thereof to afford access to the main secret compartment, including a top member movable to expose the file holder, locking means on said top engageable with a wall of the cabinet to prevent movement of the top, and a drawer normally movable to prevent operation of said locking means and abnormally operable to permit operation of said locking means.

8. In a secret cabinet, in combination, a body having a main secret compartment, and a bodily displaceable auxiliary secret compartment disposed to conceal the former, a top normally preventing access to said compartments, and removal of the auxiliary compartment, a means on said body having a normal movement and an abnormal movement, with devices coacting with the last mentioned means and the top operable to permit manipulation of the latter on abnormal movement of said means whereby the removable compartment may be displaced

and access had to the secret compartment, and a back for the cabinet operable to enable access to the main secret compartment from the rear of the body. 55

9. In a secret cabinet, a body having a public compartment space at the front, a closing means for said space, a drawer also at the front, a secret compartment between the public compartment space and the drawer, a back openable to permit access to said secret compartment, and interacting means between the drawer and the closing means 65 aforesaid, together with locking means for the back, whereby the back may be opened to permit access to said secret compartment.

10. In a secret cabinet, a body having a public compartment space at the front, a closing means for said space, a drawer also at the front, a secret compartment between the public compartment space and the drawer, a back openable to permit access to said secret compartment, an interacting means 70 between the drawer and the closing means aforesaid, together with locking means for the back, whereby the back may be opened to permit access to said secret compartment, and an auxiliary secret compartment between the back and the main secret compartment adapted to be rendered accessible by movement of the top relatively to the back. 75

11. In a secret cabinet, a body having a public compartment space at the front, a closing means for said space, a drawer also at the front, a secret compartment between the public compartment space and the drawer, a back openable to permit access to said secret compartment, an interacting means 80 between the drawer, the closing means aforesaid, and said back, together with locking means for the latter, whereby the back may be opened to permit access to said secret compartment, and an auxiliary secret compartment between the back and the main secret compartment adapted to be rendered accessible by movement of the top relatively to the back, said auxiliary secret compartment being removable and the back being 95 adapted to assume a position affording a sort of table like support. 100

In testimony whereof I affix my signature.

LEON KNASTER.
